LUG STRAP

Joseph H. Chadbourne, Pomfret, and Charles A. Burdick, Elmville, Conn., assignors to The Danielson Manufacturing Company, a corporation of Connecticut

Application October 19, 1936, Serial No. 106,409

1 Claim. (Cl. 139—153)

Our invention relates to lug straps for looms. The pounding of the picker stick against the arch or bow portion of the lug strap produces an excessive strain longitudinally of the arms or legs of the straps near whose ends are located the bolt slots. It has heretofore been attempted to mould spirally wound unsheathed textile strips impregnated with an adhesive into arched form to constitute the lug strap. In other instances 10 longitudinally disposed noncontinuous flat textile strips have been longitudinally superposed upon each other without any sheath, and saturated with an adhesive, and then moulded into final form. 15 Both the above structures being sheathless, cracked and fell to pieces in use, and in both instances the material employed had no greater resistance to longitudinal strains than to transverse strains with the result that the material 20 adjacent the bolt slots was injured or the slots deformed.

The essential objects of the present invention are to overcome the above disadvantages; and to attain the desired results in a tough, strong, 25 light and inexpensive structure.

To the above ends primarily but not exclusively our invention consists in such parts and in such combinations of parts as fall within the scope of the appended claim.

30 In the drawing,

Figure 1 is a plan view of a sheath or strip of canvass or like material with a plurality of filler cords resting in a layer thereon,

Figure 2, an end elevation of the same after 35 the cords are amassed,

Figure 3, a like elevation of the same after the sheath has been bound around the cords,

Figure 4, an end elevation of the compressing mould with the bound contents therein,

40 Figure 5, a perspective view of the moulded member after removal from the compressing mould,

Figure 6, a like view of a forming device in which the moulded member is mounted,

45 Figure 7, a perspective view of the member after removal from the forming device and after the finishing operations,

Figure 8, a horizontal section of the complete strap taken on line 8—8 of Figure 7,

50 Figure 9, a top plan view of the sheath in its initial position, a modified form of cord filling resting flat thereon, and

Figure 10, an enlarged fragmentary detail of 55 the cord filling shown in Figure 9.

Like reference characters indicate like parts throughout the views.

In constructing our novel lug strap the initial step consists in placing loosely upon a rectangular strip or sheath 15 of canvas or like material 5 a layer 16 of filling material consisting of flexible cords 17 composed of spun fiber or staple, such, for instance, as cotton, wool, or the like. As shown in Figure 1 the cords 17 extend longitudinally of the strip 15.

The described layer 16 is now impregnated 10 with an adhesive such as gelatinous glue, and the latter is also applied to the entire upper face of the strip 15. The mass 16 is then manually compressed and manipulated in such a manner as 15 to rest centrally of the strip 15 and longitudinally thereof. This position of the parts is shown in Figure 2.

The filling 16 is next bound or wrapped in the strip 15 whose binding edges overlap as at 20, 20 as shown in Figure 3.

This cylindrical package with exposed ends, being impregnated with adhesive, is of a consistency to enable transverse compression under pressure, and to this end the package is introduced into a mould 22 having a transversely rectangular moulding chamber 23 and is therein compressed. In Figure 4 the end of the mould and of the contained package are shown.

The compressed member while still moist is 30 next removed from the mould and is indicated in a general manner by the reference numeral 25 shown in Figure 5. This member is substantially oblong in shape, and in its moist condition is subjected to a shaping step to impart a U-shape 35 thereto.

In this instance this shaping is effected, as shown in Figure 6, by upper and lower clamping blocks 27 and 28 supplemented by the lateral clamping leaves 29 hinged at their upper end portions, as at 30, to the upper block 27. This imparts to the member an arched yoke portion 32 and parallel side or arm portions 33.

After the removal of the member 25 from the described or other suitable forming device its 45 free ends are trimmed if necessary, and bolt slots 35 are cut through the legs adjacent the free ends of the latter, completing the lug strap 25, as shown in Figure 7.

The spun texture of the cords 17, their severally integral character, their continuous extent, and their longitudinal disposition along the line of the greatest strain upon the lug strap, are each an important factor in the strength of the 50 55

completed structure, and contribute a measure of flexibility to the completed structure.

The employment of a sheath 15 independent of the filler core 16, completely surrounding the neck and leg portions of the strap, and of a relatively tough and impervious character, excludes the moisture of the air to a great extent, prevents disintegration of the enclosed filler core, and shields the strap from extraneous blows and 10 contacts.

In Figure 9 the wrapper or sheath 15 is shown supporting a fabric sheet 37 comprising cords 38 loosely interwoven with threads or filaments

39. The sheet 37 may be used instead of disconnected cords as a filler in the lug strap, the manipulation of this sheet and other steps in the process of construction being analogous to that already above described.

We claim:—

In a lug strap, a textile sheath, and a filler core including a plurality of separate initially unbound parallel cords lengthwise of the sheath and united by adhesive and enclosed by the 10 sheath.

JOSEPH H. CHADBOURNE.
CHARLES A. BURDICK.
